UNITED STATES PATENT OFFICE.

EDWIN WILBUR RICE, JR., OF LYNN, MASSACHUSETTS.

REGULATION OF DYNAMOS.

SPECIFICATION forming part of Letters Patent No. 397,613, dated February 12, 1889.

Application filed July 26, 1888. Serial No. 281,057. (No model.)

To all whom it may concern:

Be it known that I, EDWIN WILBUR RICE, Jr., a citizen of the United States, and a resident of Lynn, in the county of Essex and State of Massachusetts, have invented a certain new and useful Bank or Battery of Dynamo-Machines, of which the following is a specification.

My invention relates to a bank or battery of dynamo-electric machines connected in multiple to supply-mains; and it consists in the improved arrangement hereinafter described, and more particularly specified in the claims.

15 In the accompanying drawings, Figures 1, 2, and 3 illustrate diagrammatically various arrangements, all embodying my invention.

The mains supplied by the dynamos in multiple are indicated at *a b*.

20 Referring to Fig. 1, A A' indicate the armatures of dynamos, which are coupled to the mains so as to supply the same in multiple arc, and D D' indicate, respectively, the main-circuit coils for said dynamos. E¹ is an equalizing-connection applied after the manner described in my Patent No. 328,253. Field exciting-coils of constant effect for each of said dynamos are indicated by the letter E. These exciting-coils of constant effect derive 25 their current from a separate generator, G, which preferably has a field exciting-coil, H, in derivation or shunt to the armature of the generator G.

In the arrangement illustrated in Fig. 1 the 35 constant exciting-coils E of the dynamo are connected in multiple to distributing-wires fed by the generator G.

In Fig. 2 I have shown an extension of the bank or battery of dynamos to include a third 40 dynamo whose armature is indicated at A² and whose main-circuit coil is indicated at D². The equalizing-connection E² is correspondingly extended. The constant exciting-coils for the dynamos supplying the mains in multiple are 45 fed, as in Fig. 1, from a separate source, G,

having a field-coil, H, in shunt to the armature.

In Fig. 3 another modification of the system is indicated. In this case the exciting-coils E, instead of being supplied in multiple, 50 are placed in series with one another in a circuit from the separate generator G. The dynamos have their armatures connected in multiple, as before, to the mains through the field-coils D D'. The equalizing-connection 55 E² is applied as in Fig. 1.

What I claim as my invention is—

1. The improved bank or battery of dynamos herein described, comprising two or more dynamos having their armatures connected in multiple arc to the mains through field exciting-coils, an equalizing connection or connections, E², between the armature-circuits, and separate field exciting-coils E of constant effect supplied from a common separate source, as described. 60

2. The improved bank or battery of dynamos herein described, comprising two or more dynamos having their armatures connected in multiple to the main through exciting-coils, equalizing-connections between the armature-circuits, and separate field exciting-coils of constant effect supplied in multiple 70 from wires fed by the separate generator.

3. The improved bank or battery of dynamos herein described, comprising dynamo-machines having their armatures connected in multiple to the mains through field exciting-coils D D', &c., an equalizing-connection, E², between the armature-circuits, field exciting-coils E of constant effect for each dynamo, and a common supply-generator for the latter having a shunt-field, H, as described. 75

Signed at Lynn, in the county of Essex and State of Massachusetts, this 21st day of July, 80 A. D. 1888.

E. WILBUR RICE, JR.
